ATTORNEY

UNITED STATES PATENT OFFICE.

JOHN P. FLIPPO, OF COVINGTON, VIRGINIA.

TOY.

1,335,571.

Specification of Letters Patent. Patented Mar. 30, 1920.

Application filed May 27, 1919. Serial No. 300,019.

To all whom it may concern:

Be it known that I, JOHN P. FLIPPO, a citizen of the United States, and a resident of Covington, county of Alleghany, and 5 State of Virginia, have invented a new and Improved Toy, of which the following is a full, clear, and exact description.

This invention relates to toys, and more particularly it relates to a hand spun toy 10 top ornamental and attractive in appearance.

An object of the invention is to provide an ornamental hand spun top fitted with audible tone producing elements which will 15 be pleasing in appearance and use to children and which will be instructive in certain mechanical principles relating to rotation of masses.

A further object of the invention is to provide an ornamental toy fitted with audible tone producing elements which will undergo high speed rotation and emit attractive and pleasing sounds.

Another feature of the invention resides 25 in the provision of a rotating element which may be ornamented by painting color schemes thereon and which rotating colored or painted part will produce a dazzling complexity of visual appearance.

With the above principal objects, and others, in view, the invention has relation 30 to a certain combination of parts and elements, an example of which is portrayed in the following description, and specifically 35 pointed out in the appended claims, and illustrated in the accompanying drawings, wherein:

Figure 1 shows a perspective view of the device in assembled form, Fig. 2 shows a 40 sectional view of the device and Fig. 3 shows a detail view of a tone producing element employed.

Referring more in particular to the drawings, wherein the same mechanical parts 45 throughout the several views are designated by the same reference characters, the numeral 1 points out a vertically disposed spinning shaft fitted on the lower end thereof with a head 2. The head 2 and 50 spinning shaft are integrally made from a single piece of stock material such as wood, and a squared shoulder 3 is shaped at the top of the head. The upper end of the spinning shaft may be sharpened or finished 55 off as designated by 4 and provided with a squared shoulder 5. The spinning shaft

provided with the characteristic construction portrayed will be made of appropriate length and can vary according to the size of the toy to be built.

A plurality of rotating arms 6 will be fitted upon the upper stem 4 of the spinning shaft and engage the shoulder 5. The arms 6 are centrally provided with a square shaped aperture adapted to tightly fit the squared shaft and engage the shoulder 5. The rotating arms 6 may be constructed of cardboard, light wood, or other suitable material and have any appropriate shape to best suit the needs of a toy of this character. The present drawings show a pair of rotating arms mounted transversely one with the other, but it will be understood that any number of rotating arms can be employed and secured to the spinning shaft in the manner here described.

The outer extremity of each rotating arm will be fitted with a tone producing element 7. This tonal fixture or element 7 will be a bell, whistle, or other device selected by the manufacturer. The tone producing elements will preferably be attached to the underneath side of the rotating arms by a link 8 or other means.

A power arm 9 will be made of wood, or heavy paste-board and be provided with a central aperture. This power arm will be slidably confined upon the spinning shaft. Knobs 10 will be integrally shaped on the outer extremities of the power arm, and this member 9 will conform in contour and shape so as to appropriately fit the hand of the child or other person who will spin the toy.

A cord or band 11 will be passed through a hole formed in the upper portion of the spinning shaft and each end of the cord will be securely fixed or tied to each knob 10. With the power arm in downwardly limited position the cord 11 will stand angularly from the spinning shaft as shown in dotted lines.

A rotating disk 12 is pressed upon the squared shoulder 3 of the spinning head and adapted to rotate with the spinning shaft. This rotating disk may be built of any suitable material similar to the material employed for constructing the other elements. The upper face of the disk may be painted in colors or have pictures imprinted thereon. Various color schemes may be painted on the rotating disk concentrically with the spinning shaft or stripes of various colors

may be imprinted radially thereon so as to present a dazzling and commingling color appearance when the disk is rotated.

To operate the device the child will grasp 5 the power arm upon each side of the spinning shaft and exert upward and downward pressure on said arm causing it to travel slidably upon the spinning shaft. This will alternately wind and unwind the 10 cord 11 about the spinning shaft thus causing high speed rotation in first one direction and then the other of the apparatus. The rotating disk will function to generate a 15 gyroscopic effect which will tend to maintain the hand-spun top in a vertical plane for a short time after the operator has released hold upon the power arm. The rotating arms and tone producing elements will also tend to impart a gyroscopic tendency to 20 the device. The whistles or bells attached to the rotating arms will produce sound when the device undergoes operation.

This form of toy may be known as a flipper top and may be constructed under the 25 specifications and claims herein disclosed or may vary in design and operation with-

out departing from the scope and theory of the present invention.

The invention is presented to include all such changes and modifications in design 30 and form as may come within the purview of the following claims.

I claim—

1. A hand spun top comprising; a shaft, 35 a shoulder formed thereon, a head made with the spinning shaft adjacent the shoulder, a rotating disk secured to the shoulder, a shoulder formed upon the upper end of the spinning shaft, a plurality of rotating arms tightly pressed upon the upper shoulder, a power arm employed to rotate the spinning shaft, a cord attached to the power arm and wound on the shaft, and tone producing elements fitted to the arms.

2. A hand spun top comprising: a shaft, 45 a rotating disk secured to the shaft, a plurality of rotating arms fixed upon the shaft, a power arm employed to rotate the shaft, and tone producing elements carried by the arms.

JOHN P. FLIPPO.
